(57) **CLAIM**

We claim the ornamental design for a light, as shown and described.

DESCRIPTION

FIG. 1 is a front perspective view of a light.

FIG. 2 is a front view of the light shown in FIG. 1.

FIG. 3 is a rear perspective view of the light shown in FIG. 1.

FIG. 4 is a rear view of the light shown in FIG. 1.

FIG. 5 is a top view of the light shown in FIG. 1.

FIG. 6 is a bottom view of the light shown in FIG. 1.

FIG. 7 is a side view of the light shown in FIG. 1.

FIG. 8 is a side view of the light shown in FIG. 1 and illustrating two orientations of the light; and,

FIG. 9 is a front perspective view of another construction of a light and a bit holder.

A description of the appearance of the article is as follows: The present application is directed to the shape and contour of the design illustrated in the drawings.
